(57) **CLAIM**

The ornamental design for a hanging cabinet, as shown and described.

DESCRIPTION

FIG. 1 is a front elevational view of a hanging cabinet showing my new design;

FIG. 2 is a rear elevational view thereof;

FIG. 3 is an enlarged left side view thereof;

FIG. 4 is an enlarged right side view thereof;

FIG. 5 is a top plan view thereof;

FIG. 6 is a bottom plan view thereof; and,

FIG. 7 is a perspective view thereof.

The broken lines illustrate portions of the hanging cabinet that do not form part of the claimed design.

1 Claim, 7 Drawing Sheets
